[57] CLAIM

The ornamental design for a faucet handle or the like, as shown and described.

DESCRIPTION

FIG. 1 is a perspective view taken from the top, front and left side of a faucet handle or the like showing our new design;

FIG. 2 is a right side elevational view thereof, the left side being the mirror image of the right side shown;

FIG. 3 is a front elevational view thereof;

FIG. 4 is a rear elevational view thereof; and

FIG. 5 is a top plan view thereof.

FIG. 1

FIG. 2

FIG. 3

FIG. 4

FIG. 5
